THOMAS F. WILLIAMS, OF JERSEY CITY, NEW JERSEY

INTERNAL-COMBUSTION ENGINE.

1,198,094.

Specification of Letters Patent. Patented Sept. 12, 1916.

Application filed February 21, 1913. Serial No. 749,772.

To all whom it may concern:

Be it known that I, THOMAS F. WILLIAMS, a subject of the King of Great Britain, residing at Jersey City, in the county of Hudson and State of New Jersey, have invented certain new and useful Improvements in Internal-Combustion Engines; and I do hereby declare the following to be a full, clear, and exact description of the invention, such as will enable others skilled in the art to which it appertains to make and use the same, reference being had to the accompanying drawings, and to characters of reference marked thereon, which form a part of this specification.

This invention relates, generally, to improvements in internal combustion explosive engines; and, the internal combustion engines of the two-cycle type, with a view of providing a simply constructed engine and easily controlled means which enables two-cycle motors to be built, so as to have the ability of throttling at a much lower point than is now ordinarily the case, and to provide a two-cycle engine having increased flexibility and a greater variation of engine-speed, together with a higher efficiency than is now obtainable with internal combustion engines built on the four cycle principle.

With the above stated purposes in view, the present invention has for its principal object to provide an internal combustion engine of the general character hereinafter more fully set forth, and can be used and is desirable as a motor comprising only a battery of three cylinders to develop a given power having a constant torque.

The invention has for its further object to provide an engine in which the cylinder is designed to serve at one end as an explosion chamber in which the explosive mixture or gas is adapted to be exploded to produce power, and its other end serving as a pump or suction-chamber; and, the invention has for its further object to provide a piston in the form of a suitably shaped body or element which is hollow, but is closed at its ends, and is provided with means for the admission of the fresh or pure explosive mixture from the cylinder into the interior of the hollow piston and out of said piston; at the proper time, again into the portion of the cylinder which forms the firing or explosion chamber, there to be ignited by the ignition of the upper portion of a cylinder and a sparking device, the piston at the same time, piston, showing a modification of the prin-

during its movement, rapidly clearing this firing or explosion chamber of the previously exploded mixture, and thus of the spent or burnt gases, so that the firing or explosion chamber receives always a fresh supply of the explosive mixture, which is not deteriorated by the presence of remaining particles of spent gas, so that the engine is always operated with maximum efficiency.

The invention has for its further object to provide in connection with the cylinder and reciprocatory piston, an auxiliary piston-like member or element moving in time related synchronism with the piston within the cylinder for the compression of the explosive mixture within the firing or explosion chamber, and in front of the closed end of the piston, prior to the explosion of the mixture.

The invention has for its further object to provide in connection with the cylinder of the engine and its reciprocatory piston, a crank-mechanism, and a connecting rod connected with the piston and said crank-mechanism, located and operating upon the outer side of the cylinder.

Other objects of this invention not at this time more particularly enumerated will be clearly understood from the following detailed description of the present invention.

With the various objects of the present invention in view, the said invention consists, primarily, in the novel internal combustion engine of the two-cycle type hereinafter more fully set forth; and, the invention consists, furthermore, in the novel arrangements and combinations of the various devices and parts, as well as in the details of the construction of the same, all of which will be more fully described in the following specification, and then finally embodied in the clauses of the claim which are appended to and which form an essential part of this specification.

The invention is clearly illustrated in the accompanying drawings, in which:

Figure 1 is a transverse vertical sectional representation of an internal combustion engine, showing one embodiment of the principles of the present invention; and Fig. 2 is a part front elevation and part longitudinal vertical section of the engine; Fig. 3 is a detail vertical sectional representation of the upper portion of a cylinder and a piston, showing a modification of the prin-

ciples of the present invention; and Fig. 4 is a horizontal section of the same, taken on line 4—4 in Fig. 3.

Similar characters of reference are employed in the above described views, to indicate corresponding parts.

Referring now to the said drawings, the reference-character 1, in Figs. 1 and 2 of the drawings, indicates a suitably formed cylinder, which is suitably closed and sealed upon its upper end by means of a suitably formed cylinder-head 2. The lower open-ended portion of said cylinder is made with a preferably outwardly flaring supporting portion, as 3, which is flanged, as at 4, and is suitably secured to a shell-like member or element, as 5, provided with suitably formed and suitably disposed bearings, as 6, in which is rotatably mounted a crank-shaft 7, 10 provided with a suitable crank, as 8. Preferably surrounding that portion of the cylinder 1 which forms the firing or explosion chamber, indicated by the reference-character 9, is a cooling jacket 10 for the reception and circulation around the cylinder of a suitable cooling medium, as water or the like.

In one side, and located in the upper portion of the cylinder 1 is an inlet-port, as 11, 30 with which is adapted to be connected the usual form of carburetor, and the reference-characters 12 and 13 are a pair of suitably disposed exhaust or outlet-ports. The said cylinder 1 is also provided with another arrangement of inlet-ports 14 and 15 which are connected by a by-pass 16, indicated in dotted outline in said Fig. 1, and for the purpose hereinafter more fully specified. A screw-threaded opening, as 17, is also provided in the side of the cylinder 1, and located at a point between the said ports 14 and 15, and communicating also with the interior of the cylinder 1, and preferably with an annularly grooved or recessed portion 18 of the cylinder, substantially as shown in said Fig. 1. Suitably screwed into this screw-threaded opening 17 is a suitable spark-plug 19, of any usual and well-known form and construction.

50 Slidably disposed in the lower open-ended portion of the cylinder 1 is a plunger or piston-like element or closing member, as 20, provided preferably with packing rings 21. This plunger or piston-like element is 55 made in the form of an inverted cup, as shown, having a closed top 22, and provided at its lower open part with an annular marginal bead-like portion, 23, for the arrangement of a coiled spring 24 between said bead-like portion 23 and the part 25 of the cylinder, the coils of said spring encircling the said element or member 20, for the purposes to be presently described. Connected with the inner and chambered portion of said 60 plunger or piston-like member or element 20

are suitably forked members 26 extending from the lower open portion of said plunger or piston-like member or element 20 and terminating in guiding fingers or extensions 27. These fingers or extensions 27 extend on opposite sides of the previously-mentioned crank-shaft 7, and are located upon opposite sides of a suitably shaped cam, as 28, which is mounted upon and suitably secured to the said crank-shaft. At suitable points, 75 located above said pairs of guiding fingers or extensions 27, each member 26 is provided with a perforation, and secured in said perforations are the end-portions of a pin 29 which extends across the space between the said members 26, and has rotatably arranged thereon an anti-friction roller 30 which is in rolling engagement with the cam-surface of said cam 28, for lifting the said plunger or piston-like member or element 20 the proper time, and to compress the coils of the spring 24, and at other times permitting the spring to act, so as to move the said plunger or piston-like member 20 in a downward direction. Slidably arranged within the cylinder 1, above the said plunger or piston-like member or element 20 is a power-piston, which, in the construction represented in Figs. 1 and 2 of the drawings, consists of a hollow or tubular portion 31, connected at its lower end-portion with a hollow piston-head, as 32, which is closed, as at 33, and is provided with suitably disposed ports or openings 34, adapted to be brought into registration 95 with the port 15. The said piston-head 32 may also be provided with piston rings 35, if desired. The upper end-portion of said hollow or tubular portion 31 terminates in an outwardly flaring or funnel-shaped part 100 36, which is internally screw-threaded, as at 37, and has a seat-like part 38 for the reception and the securing in-said part 36 of a valve-member 39. This valve-member has a downwardly extending and fixed tubular guide 40, in which is slidably disposed a valve-stem 41, provided with an enlargement 42. Connected with said stem 41 is a valve-disk or plate 43, normally forced upon a seat 44 with which the valve-member 39 115 is provided, by a coiled spring 45, which encircles said fixed tubular guide. Connected with and extending downwardly from the annular marginal edge-portion of the said outwardly flaring or funnel-shaped part 36 120 is an upper and hollow piston-head 46 suitably registering with the interior of the cylinder 1. This piston-head 46 may be provided with suitably disposed piston rings 47. The said hollow or tubular portion 31 125 of the piston is also provided with an enlargement, as 48, and a laterally extending bearing-portion 49, in which is arranged a connecting rod-pin 50, said pin extending through and being movably arranged in an 130

elongated opening 51, of proper length, in the side of the cylinder 1. Suitably connected with and arranged between said pin 50 and the crank 8 of the crank-shaft 7, and arranged upon the outer side of the cylinder 1, is a connecting rod 52. The upper piston-head 46 is of such length that during its downward movement, and at the end of its full downward stroke it will close the opening 51, so that there can be no escape and loss of the fresh supply of gaseous mixture above the cylinder-head 46 from within the cylinder 1.

In lieu of the form of piston shown in Figs. 1 and 2 of the drawings, the construction represented in Figs. 3 and 4, may be employed. In this modified construction of engine, the cylinder which is indicated by the reference-character 53, is formed upon its upper end-portion with an annular enlargement, as 54, upon which is secured in any suitable manner the cylinder-head 55, thus providing the cylinder with a chambered portion 56 of greater area than the cross-sectional area of the main body of the cylinder. Within this chambered portion 56, and in alignment with the main walls of the cylinder, is a suitably formed ring-like portion 57 which is connected with the main part of the cylinder by the parts 57', so as to provide a series of openings, as 58, as will be clearly seen from an inspection of Fig. 4 of the drawings. The main portion of the hollow piston in this construction is similar to that of the piston represented in Figs. 1 and 2 of the drawings except that the outwardly flaring or funnel-shaped part 36 of the piston is formed with upwardly extending parts 59, corresponding to the parts 57', and with which parts 59 is connected a piston-head 60. The said parts 59, with the annular marginal portions of the said piston-head 60 and the said outwardly flaring or funnel-shaped part 36 of the piston, also provide a series of openings, as 61, which correspond to the openings 58, and at proper times register with said openings 58, so as to provide suitable ports of admission from the said chambered portion 56 into the interior of the hollow piston, as clearly shown in said Figs. 3 and 4 of the drawings, and for the purpose to be presently more fully described.

Having in the foregoing specification described the general construction of internal combustion engine embodying the principles of the present invention, I will now briefly set forth the operation of the same.

Referring now to Figs. 1 and 2 of the drawings, let us suppose that the piston is on its downward stroke. Of course, a vacuum is produced above the upper end-portion of the hollow piston during the downward movement of the piston, the

gaseous mixture from the carbureter which is connected with the inlet port 11 flowing into this vacuum, as soon as the piston-head 46 has passed the said port 11, and filling the space in the upper portion of the cylinder 1, formed between the cylinder-head 2 and the upper end-portion of the downwardly moving piston. At the same time, the previously exploded or expended gas located in the firing-chamber 9 of the cylinder 1, directly beneath the lower piston-head 32 of the piston, is rapidly expelled through the exhaust ports 13 and 12, the plunger or piston-like member or element 20 remaining immovably in the position indicated in Fig. 1, during the rolling movement of the roller 30 upon the concentric surface-portion 62 of the cam 28, and until the cam-surface 63 is reached. Assuming, also, that the hollow or tubular portion 31 of the power piston had also been previously filled with a supply of non-expended gaseous mixture, this mixture being imprisoned in the portion 31, until the ports or outlets 34, are brought opposite the port 15. Immediately this imprisoned and compressed gaseous mixture within said portion 31 will pass into the port 15, through the by-pass 16, and out of the port 14, into the firing chamber 9, directly beneath the closed end 33 of the lower piston-head 32. Just prior to this action of the mixture, however, and during the rotation of the crank shaft 7, the roller 30 has moved upon the cam-surface 63 of the cam 28, whereby the plunger or piston-like member 20 is moved farther up into the lower part of the cylinder 1, acting as a mechanically operated valve to first close the exhaust port 12, and the roller 30 next moving upon the cam-surface 63', the inlet-port 14 is closed, the closed end 22 of said plunger or piston-like member 20, in addition to the descending piston, at the same time acting as a means for compressing the admitted gaseous mixture in the firing chamber 9, as will be evident. At this time the explosion or firing of the admitted gaseous mixture takes place, and, the roller 30 now riding upon the concentric surface 64 of the cam 28, the plunger or piston-like element 20 is for a time immovably retained in its raised position, so as to maintain the complete closure of the ports 12 and 14, the power-piston is once more forced upwardly into its starting position indicated in said Figs. 1 and 2 of the drawings. During the upward travel of the power-piston within the cylinder 1, the roller 30 has traveled the complete length of the concentric surface 64, at the end of which it drops upon the angular surface-portion 65, whereby the compressed coils of the spring 24 coacting with the weight of the member or element 20, cause the latter to again move

in a downward direction, so as to once more open the ports 14 and 12. During the upward or return movement of the power-piston, the second charge of gaseous mixture, which as has been stated, was admitted into the space between the cylinder-head 2 and the upper portion of the power-piston, is compressed and forces the valve-disk or plate 43 from the valve-seat 44, so that the charge of the gaseous mixture will immediately enter the hollow or tubular part 31 of the power-piston, and to be withdrawn therefrom into the firing chamber in the manner hereinabove set forth. As soon as the power-piston has reached its full upward stroke, the spring 45, with the gaseous mixture now back of the valve-disk or plate 43, will seat the said disk or plate 43 upon the valve-seat 44, so that the upper end portion of the hollow power-piston is once more closed.

With the construction of engine represented in said Figs. 3 and 4 of the drawings, the general operation and result is the same as that set forth above in connection with the construction illustrated in said Figs. 1 and 2. During the upward or return stroke of the piston 36 within the cylinder 53, the gaseous mixture is compressed in the chambered portion 56, and when the ports 61 in the piston register with the ports 58, the mixture will immediately pass into the hollow or tubular power-piston in which the gaseous mixture is held by the closing of the ports 61 by the cylindrical wall of the cylinder 52, upon the downward movement of the piston, and from the lower portion of which piston the gaseous mixture is admitted into the firing chamber of the cylinder in the same manner as hereinabove described with the construction of engine illustrated in Figs. 1 and 2 of the drawings.

Of course, I am aware that changes may be made in the general arrangements and combinations of the several devices and parts, as well as in the details of the construction of the said parts, as described in the foregoing specification, without departing from the scope of the invention as set forth in the said specification and as defined in the clauses of the claim which are appended thereto. Hence, I do not limit my present invention to the exact arrangement and combinations of the various devices and parts as described in the said specification, nor do I confine myself to the exact details of the construction of the said parts as illustrated in the accompanying drawings.

I claim:

1. An internal combustion engine comprising a cylinder having an inlet and an exhaust port, a chambered piston controlling said ports, and said piston being provided in one portion with a valve for admitting the explosive or gaseous mixture di-

rectly into the said piston and said piston having a port for admitting the mixture from the said piston into the firing chamber of said cylinder, combined with an auxiliary piston-like element movably arranged in said cylinder and moving in time related synchronism with said chambered piston. 70

2. An internal combustion engine comprising a cylinder having an inlet and an exhaust port, a chambered piston controlling said ports, and said piston being provided in one portion with a valve for admitting the explosive or gaseous mixture directly into the said piston and said piston having a port for admitting the mixture from the said piston into the firing chamber of said cylinder, combined with an auxiliary and spring-controlled piston-like element movably arranged in said cylinder and moving in time related synchronism with said chambered piston. 75 80

3. An internal combustion engine comprising a cylinder having an inlet and an exhaust port, a chambered piston controlling said ports, said piston being provided at one end with a valve-receiving opening, a valve in said opening for the admission of the explosive or gaseous mixture into said chambered piston, and means connected with the other end of said piston for passing the explosive or gaseous mixture from said chambered piston into the firing chamber of said cylinder, combined with an auxiliary piston-like element movably arranged in said cylinder and moving in time-related synchronism with said chambered piston. 90 95

4. An internal combustion engine comprising a cylinder having an inlet and an exhaust-port, a chambered piston controlling said port, said piston being provided at one end with a valve-receiving opening, a valve in said opening for the admission of the explosive or gaseous mixture into said chambered piston, and means connected with the other end of said piston for passing the explosive or gaseous mixture from said chambered piston into the firing chamber of said cylinder, combined with an auxiliary and spring-controlled piston-like element movably arranged in said cylinder and moving in time-related synchronism with said chambered piston. 100 110

5. An internal combustion engine comprising a cylinder having an inlet and an exhaust port, said cylinder being also provided with a pair of inlet-ports in communication with the firing chamber of the cylinder, said pair of inlet-ports being connected by means of a by-pass, a chambered piston controlling said inlet and exhaust ports, said piston being provided in one portion with a valve for admitting the explosive or gaseous mixture directly into said piston, the said piston being provided in its other end- 115 120 125 130

- portion with an outlet-port adapted to be brought into registration with one of said pair of inlet-ports of the cylinder for the admission of the explosive or gaseous mixture from the chambered piston first into said by-pass and into the other of said pair of inlet-ports, and from said last-mentioned inlet-port into the firing chamber of the cylinder, combined with an auxiliary piston-like element movably arranged in said cylinder and moving in time-related synchronism with said chambered piston.
6. An internal combustion engine comprising a cylinder having an inlet and an exhaust port, said cylinder being also provided with a pair of inlet-ports in communication with the firing chamber of the cylinder, said pair of inlet-ports being connected by means of a by-pass, a chambered piston controlling said inlet and exhaust ports, means connected with the one end of said piston for admitting the explosive or gaseous mixture into said piston, the said piston being provided in its other end-portion with an outlet-port adapted to be brought into registration with one of said pair of inlet-ports of the cylinder for the admission of the explosive or gaseous mixture from the chambered piston first into said by-pass and into the other of said pair of inlet-ports, and from said last-mentioned inlet-port into the firing chamber of the cylinder, combined with an auxiliary and spring-controlled piston-like element movably arranged in said cylinder and moving in time-related synchronism with said chambered piston.
7. An internal combustion engine comprising a cylinder having an inlet and an exhaust-port, said cylinder being also provided with a pair of inlet-ports in communication with the firing chamber of the cylinder, said pair of inlet-ports being connected by means of a by-pass, a chambered piston controlling said inlet and exhaust ports, said piston being provided at one end with a valve-receiving opening, a valve in said opening for the admission of the explosive or gaseous mixture into said chambered piston, the said piston being provided in its other end-portion with an outlet-port adapted to be brought into registration with one of said pair of inlet-ports of the cylinder for the admission of the explosive or gaseous mixture from the chambered piston first into said by-pass and into the other of said pair of inlet-ports, and from said last-mentioned inlet-port into the firing chamber of the cylinder, combined with an auxiliary piston-like element movably arranged in said cylinder and moving in time-related synchronism with said chambered piston.
8. An internal combustion engine comprising a cylinder having an inlet and an exhaust-port, said cylinder being also provided with a pair of inlet-ports in communication with the firing chamber of the cylinder, said pair of inlet-ports being connected by means of a by-pass, a chambered piston controlling said inlet and exhaust ports, said piston being provided at one end with a valve-receiving opening, a valve in said opening for the admission of the explosive or gaseous mixture into said chambered piston, the said piston being provided in its other end-portion with an outlet-port adapted to be brought into registration with one of said pair of inlet-ports of the cylinder for the admission of the explosive or gaseous mixture from the chambered piston first into said by-pass and into the other of said pair of inlet-ports, and from said last-mentioned inlet-port into the firing chamber of the cylinder, combined with an auxiliary piston-like element movably arranged in said cylinder and moving in time-related synchronism with said chambered piston.
9. An internal combustion engine comprising a cylinder having an open end and an inlet and an exhaust port, said cylinder being provided in its side with an elongated opening, a chambered piston controlling said ports, means connected with said piston for admitting the explosive or gaseous mixture into the said piston and from the said piston into the firing chamber of said cylinder, a crank-casing connected with the open end of said cylinder, a crank-shaft mounted in said crank-casing, a bearing within said chambered piston, a connecting rod-pin mounted in said bearing, said pin extending from the side of the piston and into and from the elongated opening in the side of the cylinder, and a connecting rod between said pin and the crank-shaft, said connecting rod being arranged upon the outside of the cylinder.
10. An internal combustion engine comprising a cylinder having an open end and an inlet and an exhaust port, said cylinder being provided in its side with an elongated opening, a chambered piston controlling said ports, means connected with said piston for admitting the explosive or gaseous mixture into the said piston and from the said piston into the firing chamber of said cylinder, a crank-casing connected with the open end of said cylinder, a crank-shaft mounted in said crank-casing, a bearing within said chambered piston, a connecting rod-pin mounted in said bearing, said pin extending from the side of the piston and into and from the elongated opening in the side of the cylinder, and a connecting rod between said pin and the crank-shaft, said connecting rod being arranged upon the outside of the cylinder.

the cylinder, and means operated from the crank-shaft for moving said piston-like element in time-related synchronism with the chambered piston.

5 11. An internal combustion engine comprising a cylinder having an open end and an inlet and an exhaust port, said cylinder being provided in its side with an elongated opening, a chambered piston controlling 70 said ports, means connected with said piston for admitting the explosive or gaseous mixture into the said piston and from the said piston into the firing chamber of said cylinder, a crank-casing connected with the 75 open end of said cylinder, a crank-shaft mounted in said crank-casing, a bearing within said chambered piston, a connecting rod-pin mounted in said bearing, said pin extending from the side of the piston and into and from the elongated opening in the side of the cylinder, and a connecting rod between said pin and the crank-shaft, said connecting rod being arranged upon the outside of the cylinder, combined with an auxiliary 80 chambered and spring-controlled piston-like element movably arranged in the open end of the cylinder, guiding fingers connected with the interior of said piston-like element and extending from the open end thereof, a pin connected with and extending across the space between said fingers, a roller upon said pin, and a cam upon 85 said crank-shaft in engagement with said roller for moving said piston-like element in time-related synchronism with the chambered piston.

12. An internal combustion engine comprising a cylinder having an open end and an inlet and an exhaust port, said cylinder being provided in its side with an elongated 90 opening, a chambered piston controlling said ports, means connected with said piston for admitting the explosive or gaseous mixture into the said piston and from the said piston into the firing chamber of said cylinder, a crank-casing connected with the open end of said cylinder, a crank-shaft mounted in said crank-casing, a bearing within said chambered piston, a connecting rod-pin mounted in said bearing, said pin extending 95 from the side of the piston and into and from the elongated opening in the side of the cylinder, and a connecting rod between said pin and the crank-shaft, said connecting rod being arranged upon the outside of the cylinder, combined with an auxiliary chambered piston-like element movably arranged in the open end of the cylinder, guiding fingers connected with the interior of said piston-like element and extending 100 from the open end thereof, a pin connected with and extending across the space between said fingers, a roller upon said pin, and a cam upon said crank-shaft in engagement with said roller for moving said piston-like element in time-related synchronism with the chambered piston.

13. An internal combustion engine comprising a cylinder having an open end and an inlet and an exhaust port, said cylinder being provided in its side with an elongated 105

opening, a chambered piston controlling said ports, means connected with said piston for admitting the explosive or gaseous mixture into the said piston and from the said piston into the firing chamber of said cylinder, a crank-casing connected with the open end of said cylinder, a crank-shaft mounted in said crank-casing, a bearing within said chambered piston, a connecting rod-pin mounted in said bearing, said pin extending from the side of the piston and into and from the elongated opening in the side of the cylinder, and a connecting rod between said pin and the crank-shaft, said connecting rod being arranged upon the outside of the cylinder, combined with an auxiliary chambered and spring-controlled piston-like element movably arranged in the open end of the cylinder, guiding fingers connected with the interior of said piston-like element and extending from the open end thereof, a pin connected with and extending across the space between said fingers, a roller upon said pin, and a cam upon 110 said crank-shaft in engagement with said roller for moving said piston-like element in time-related synchronism with the chambered piston.

14. An internal combustion engine comprising a cylinder having an open end and an inlet and exhaust port, said cylinder being provided in its side with an elongated opening, and also with a pair of inlet-ports in communication with the firing chamber of the cylinder, said pair of inlet-ports being connected by means of a by-pass, a chambered piston controlling said inlet and exhaust ports, means connected with one end of said piston for admitting the explosive or gaseous mixture into said piston, the said piston being provided in its other end-portion with an outlet-port adapted to be brought into registration with one of said pair of inlet-ports of the cylinder for the admission of the explosive or gaseous mixture from the chambered piston first into said by-pass and into the other of said pair of inlet-ports, and from said last-mentioned inlet-port into the firing chamber of the cylinder, a crank-casing connected with the open end of said cylinder, a crank-shaft mounted in said crank-casing, a bearing within said chambered piston, a connecting rod-pin mounted in said bearing, said pin extending from the side of the piston and into and from the elongated opening in the side of the cylinder, and a connecting rod between said pin and the crank-shaft, said connecting rod being arranged upon the outside of the cylinder.

15. An internal combustion engine comprising a cylinder having an open end and an inlet and exhaust port, said cylinder being provided in its side with an elongated opening, and also with a pair of inlet-ports 115

in communication with the firing chamber of the cylinder, said pair of inlet-ports being connected by means of a by-pass, a chambered piston controlling said inlet and exhaust ports, means connected with one end of said piston for admitting the explosive or gaseous mixture into said piston, the said piston being provided in its other end-portion with an outlet-port adapted to be brought into registration with one of said pair of inlet-ports of the cylinder for the admission of the explosive or gaseous mixture from the chambered piston first into said by-pass and into the other of said pair of inlet-ports, and from said last-mentioned inlet-port into the firing chamber of the cylinder, a crank-casing connected with the open end of said cylinder, a crank-shaft mounted in said crank-casing, a bearing within said chambered piston, a connecting rod-pin mounted in said bearing, said pin extending from the side of the piston and into and from the elongated opening in the side of the cylinder, and a connecting rod between said pin and the crank-shaft, said connecting rod being arranged upon the outside of the cylinder, combined with an auxiliary piston-like element movably arranged in the open end of the cylinder, and means operated from the crank-shaft for moving said piston-like element in time-related synchronism with the chambered piston.

16. An internal combustion engine comprising a cylinder having an open end and an inlet and exhaust port, said cylinder being provided in its side with an elongated opening, and also with a pair of inlet-ports in communication with the firing chamber of the cylinder, said pair of inlet-ports being connected by means of a by-pass, a chambered piston controlling said inlet and exhaust ports, means connected with one end of said piston for admitting the explosive or gaseous mixture into said piston, the said piston being provided in its other end-portion with an outlet-port adapted to be brought into registration with one of said pair of inlet-ports of the cylinder for the admission of the explosive or gaseous mixture from the chambered piston first into said by-pass and into the other of said pair of inlet-ports, and from said last-mentioned inlet-port into the firing chamber of the cylinder, a crank-casing connected with the open end of said cylinder, a bearing within said chambered piston, a connecting rod-pin mounted in said bearing, said pin extending from the side of the piston and into and from the elongated opening in the side of the cylinder, and a connecting rod between said pin and the crank-shaft, said connecting rod being arranged upon the outside of the cylinder, combined with an auxiliary piston-like element movably arranged in the open end of the cylinder, and means operated from the crank-shaft for moving said piston-like element in time-related synchronism with the chambered piston.

17. An internal combustion engine comprising a cylinder having an open end and an inlet and exhaust port, said cylinder being provided in its side with an elongated opening, and also with a pair of inlet-ports in communication with the firing chamber of the cylinder, said pair of inlet-ports being connected by means of a by-pass, a chambered piston controlling said inlet and exhaust ports, means connected with one end of

said piston for admitting the explosive or gaseous mixture into said piston, the said piston being provided in its other end-portion with an outlet-port adapted to be brought into registration with one of said pair of inlet-ports of the cylinder for the admission of the explosive or gaseous mixture from the chambered piston first into said by-pass and into the other of said pair of inlet-ports, and from said last-mentioned inlet-port into the firing chamber of the cylinder, a crank-casing connected with the open end of said cylinder, a crank-shaft mounted in said crank-casing, a bearing within said chambered piston, a connecting rod-pin mounted in said bearing, said pin extending from the side of the piston and into and from the elongated opening in the side of the cylinder, and a connecting rod between said pin and the crank-shaft, said connecting rod being arranged upon the outside of the cylinder, combined with an auxiliary chambered piston-like element movably arranged in the open end of the cylinder, guiding fingers connected with the interior of said piston-like element and extending from the open end thereof, a pin connected with and extending across the space between said fingers, a roller upon said pin, and a cam upon said crank-shaft in engagement with said roller for moving said piston-like element in time-related synchronism with the chambered piston.

18. An internal combustion engine comprising a cylinder having an open end and an inlet and exhaust port, said cylinder being provided in its side with an elongated opening, and also with a pair of inlet-ports in communication with the firing chamber of the cylinder, said pair of inlet-ports being connected by means of a by-pass, a chambered piston controlling said inlet and exhaust ports, means connected with one end of said piston for admitting the explosive or gaseous mixture into said piston, the said piston being provided in its other end-portion with an outlet-port adapted to be brought into registration with one of said pair of inlet-ports of the cylinder for the admission of the explosive or gaseous mix-

ture from the chambered piston first into said by-pass and into the other of said pair of inlet-ports, and from said last-mentioned inlet-ports into the firing chamber of the cylinder, a crank-casing connected with the open end of said cylinder, a crank-shaft mounted in said crank-casing, a bearing within said chambered piston, a connecting rod-pin mounted in said bearing, said pin 10 extending from the side of the piston and into and from the elongated opening in the side of the cylinder, and a connecting rod between said pin and the crank-shaft, said connecting rod being arranged upon the out- 15 side of the cylinder, combined with an auxiliary chambered and spring-controlled piston-like element movably arranged in the

open end of the cylinder, guiding fingers connected with the interior of said piston-like element and extending from the open 20 end thereof, a pin connected with and extending across the space between said fingers, a roller upon said pin, and a cam upon said crank-shaft in engagement with said roller for moving said piston-like element 25 in time-related synchronism with the chambered piston.

In testimony, that I claim the invention set forth above I have hereunto set my hand this 19th day of February, 1913.

THOMAS F. WILLIAMS.
